CLAIM

The ornamental design for a light emitting diode bulb connector, as shown and described.

DESCRIPTION

FIG. 1 is a perspective view of a light emitting diode bulb connector showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines shown in the figures are environmental only and form no part of the claimed design. The inventors reserve the right to claim any part, portion, element or combination thereof of the disclosed design.
